[57] CLAIM

The ornamental design for the flexible, interlocking toy piece capable of assembly into polyhedral shapes, as shown.

DESCRIPTION

FIG. 1 is a perspective view of a flexible, interlocking toy piece capable of assembly into polyhedral shapes showing my new design;

FIG. 2 is a front elevational view thereof;

FIG. 3 is a left side elevational view thereof;

FIG. 4 is a right side elevational view thereof;

FIG. 5 is a rear elevational view thereof;
FIG. 6 is a perspective view of a modified embodiment of the design shown in FIGS. 1-5;

FIG. 7 is a front elevational view thereof;

FIG. 8 is a left side elevational view thereof;

FIG. 9 is a right side elevational view thereof; and,

FIG. 10 is a rear elevational view thereof.
